The ornamental design for a skin toning device, as shown and described.

DESCRIPTION

FIG. 1 is a perspective view of a skin toning device in accordance with the design;

FIG. 2 is an additional perspective view thereof in use;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is a bottom plan view thereof.

Any broken lines present in the drawings form no part of the claimed design.
